DESIGN FOR A PROJECTOR

Henry F. Kurtz, Rochester, and Bernard J. Wolfe,
Greece, N. Y., assignors to Bausch & Lomb Optical
Company, Rochester, N. Y., a corporation
of New York

Application December 7, 1938, Serial No. 81,628

Term of patent 14 years

To all whom it may concern:

Be it known that we, Henry F. Kurtz and Bernard J. Wolfe, citizens of the United States and residents of Rochester and the town of Greece, respectively, in the county of Monroe and State of New York, have invented a new, original, and ornamental Design for Projector, of which the following is a specification, reference being had to the accompanying drawing, forming a part thereof.

The figure is a perspective view of a projector showing our new design, the opposite side of which is substantially the same in appearance as the side shown.

We claim:

The ornamental design for a projector, as shown and described.

HENRY F. KURTZ.
BERNARD J. WOLFE.
